Primary Examiner — John A Voytek

(57) **CLAIM**

The ornamental design for a hand-eye coordination training device, as shown and described.

DESCRIPTION

FIG. 1 is a top view of a hand eye coordination training device according to the invention;

FIG. 2 is a bottom view of the hand eye coordination training device according to the invention;

FIG. 3 is a first side view of the hand eye coordination training device according to the invention;

FIG. 4 is a second side view of the hand eye coordination training device according to the invention;

FIG. 5 is a third side view of the hand eye coordination training device according to the invention;

FIG. 6 is a fourth side view of the hand eye coordination training device according to the invention; and,

FIG. 7 is a perspective view of the hand eye coordination training device according to the invention.

1 Claim, 7 Drawing Sheets
